ATTORNEY

UNITED STATES PATENT OFFICE.

LEWIS NEWELL, OF UNION HILL, NEW JERSEY.

ENGINE.

1,310,767.

Specification of Letters Patent. Patented July 22, 1919.

Application filed July 6, 1918. Serial No. 243,621.

To all whom it may concern:

Be it known that I, LEWIS NEWELL, a citizen of the United States, residing at Union Hill, in the State of New Jersey, have invented certain new and useful Improvements in Engines, of which the following is a specification.

This invention relates to gasoline or internal combustion engines and has for its object the production of a simple and efficient means for developing a maximum amount of power from a minimum number of cylinders.

Another object of this invention is the production of a simple and efficient air cooling means for the engine whereby a complete circulation of air may be caused to extend around or pass around the explosive cylinder.

With these and other objects in view this invention consists of certain novel constructions, combinations and arrangements of parts as will be hereinafter fully described and claimed.

In the drawings:

Figure 1 is a vertical section through the explosive engine.

Fig. 2 is a section taken on line 2—2 of Fig. 1.

Fig. 3 is a section taken on line 3—3 of Fig. 1.

Fig. 4 is a section taken on line 4—4 of Fig. 1.

By referring to the drawings, it will be seen that 1 designates a crank casing through which extends a crank shaft 2 having a crank portion 3 and a crank portion 4 formed thereon. A cylinder 5 is supported upon the crank casing 1 and this cylinder 5 is provided with an open upper end 6. An air cooling jacket 7 fits over the cylinder 5 and is held in spaced relation to the cylinder 5 by means of the ribs 8. A head plate 9 is secured to the jacket 7 by means of suitable bolts 10 passing through the respective flanges 11 carried by the head 9 and the jacket 7, as shown clearly in Figs. 1 and 2 of the drawings. The cylinder 5 is provided with a pair of laterally extending neck portions 12 which may be secured to the cylinder 5 in any suitable or convenient manner and constitute intake and exhaust means. These neck portions 12 extend into the sockets 13 formed in the jacket 7 for the purpose of permitting the neck portions 12

to communicate with the intake and exhaust manifold casings 14 and 15.

The jacket 7 supports the intake and exhaust manifold casings 14 and 15 and an intake tube 16 is secured to the intake manifold 14, an exhaust tube 17 being secured to the exhaust manifold casing 15. The intake manifold casing 14 carries a spark plug 18 of any suitable or desired construction for the purpose of igniting the gases, within the intake manifold casing 14. Each of the manifold casings 14 and 15 carries a control valve 19 which is operated by means of a valve stem 20, the valve stem 20 being actuated in the usual manner by means of the operating cams 21, in this way controlling the admission and exhaust of gases to and from the explosive cylinder 5.

A suction piston head 22 is carried in the upper end of the cylinder 5 and an auxiliary piston head 23 is carried within the lower end of the cylinder 5. The piston head 22 carries a piston rod 24 which piston rod passes through the piston head 23 as shown in Fig. 1, the piston head 23 carrying a packing 25 for causing a tight joint to be formed around the piston rod 24. The lower end of the piston rod 24 is connected to the crank portion 3 by means of a link connection 26. The piston head 23 is provided with a depending neck 23' having a projection 26' formed upon one side thereof. A notch 27 is formed in the under face of the projection 26' within which notch 27 is pivotally mounted the upper end 28 of the operating link 29 by means of a pin 30.

The depending neck 23' is provided with longitudinally extending slots 27' upon each side thereof to permit the link 26 to freely operate with the crank shaft 2. The neck 23' is provided with oppositely arranged channels 28' within which channels work the lugs 29' formed upon the lower end of the plunger 24 for guiding the plunger rod 24 in its movement.

The operation of the device is as follows:

The intake gases will pass through the port 31 from the manifold casing 14 and be admitted into the cylinder 5, the gases being exploded by means of the spark plug 18. The explosion of the gases will cause the piston heads 22 and 23 to move apart and in this manner rotate the shaft 2. As the piston 22 moves upwardly, the air within the jacket 7 will be forced out through the lower

open end 32 of the jacket, and upon the inward movement of the head 22, fresh air will be drawn into the jacket, in this way keeping an efficient circulation of air around the cylinder 5 for the purpose of cooling the same. The burnt gases, upon the upward movement of the piston 23 will be forced out through the port 33 and into the exhaust manifold 15, the valve 19 within the exhaust manifold being open at a proper time to permit the exhaust gases to be discharged through the exhaust pipe 17. It of course should be understood that the valves 19 are operated at proper times for controlling the admission and exhaust of gases to and from the explosive cylinder.

It should be of course understood that certain obvious detail mechanical changes may be made in the present device without departing from the spirit of the invention, so long as these changes fall within the scope of the appended claims.

What is claimed is:—

1. An engine of the class described comprising a cylinder, a suction piston head carried within said cylinder, an auxiliary piston head working below said suction piston head, said auxiliary piston head provided with a depending neck portion, a piston rod extending through said neck portion and supporting said suction piston head, said piston rod provided with a plurality of lugs formed upon the sides thereof, said neck portion provided with a plurality of grooves formed therein for constituting a track for said lugs, a link connected to the lower end of said piston rod, a crank shaft, said link connected to said crank shaft, and means connecting said crank shaft to said auxiliary piston.
2. An engine of the class described comprising a cylinder, a suction piston head carried within said cylinder, an auxiliary piston head working below said suction piston head, said auxiliary piston head provided with a depending neck portion, a piston rod extending through said neck portion and supporting said suction piston head, said

piston rod provided with a plurality of lugs formed upon the sides thereof, said neck portion provided with a plurality of grooves formed therein for constituting a track for said lugs, a link connected to the lower end of said piston rod, a crank shaft, said link connected to said crank shaft, means connecting said crank shaft to said auxiliary piston, said neck portion provided with a plurality of slots formed in the sides thereof for permitting the free operation of said link and piston rod as said crank shaft is operated.

3. An engine of the class described comprising a cylinder, a plurality of piston heads mounted within said cylinder, one of said piston heads provided with a depending neck portion, a piston rod extending through said neck portion and supporting the other piston head, said neck portion and piston rod provided with guiding means for facilitating the reciprocation of said piston rod through said neck portion, a crank shaft, means connecting said rod to said crank shaft, and means connecting said neck portion to said crank shaft.

4. An engine of the class described comprising a cylinder, a plurality of pistons working within said cylinder, one of said pistons provided with a depending neck portion, a piston rod extending through said neck portion and supporting the other piston head, guiding means carried by said piston rod, said neck portion provided with guiding means coöperating with said first mentioned guiding means, a crank shaft, a link connected to said crank shaft and engaging said piston rod, and a link engaging said neck portion and also engaging said crank shaft for facilitating the operation of said crank shaft as said pistons are operated.

In testimony whereof I affix my signature in presence of two witnesses.

LEWIS NEWELL.
